UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

SWITCH-OPERATING MECHANISM.

Application filed October 23, 1923. Serial No. 670,383.

To all whom it may concern:

Be it known that I, CARL H. BISSELL, a citizen of the United States, and a resident of Syracuse, in the county of Onondaga and State of New York, have invented a certain new and useful Switch-Operating Mechanism, of which the following is a specification.

This invention relates to electric switches and has for its object a particularly simple and efficient switch operating mechanism and locking mechanism for holding the switch in "on" position and particularly simple and efficient locking and releasing means for holding and releasing when operated the handle and the switch.

The invention consists in the novel features and combinations and constructions hereinafter set forth and claimed.

20 In describing this invention reference is had to the accompanying drawings in which like characters designate corresponding parts in all the views.

Figure 1 is a plan view of a switch embodying my invention.

Figure 2 is a side elevation thereof, partly in section.

Figure 3 is a detail view of parts of the release means.

30 Figure 4 is a diagrammatic view of the wiring of the low voltage release mechanism.

This switch operating mechanism, comprises generally a movable switch member, operating means therefor, comprising a handle and motion transmitting means between the handle and the switch member, the handle being connected to the motion transmitting means by a lost motion connection, which permits movement of the handle relatively to the transmitting means, particularly in a retrograde direction, locking means movable automatically into operative position for holding the motion transmitting means and switch member in "on" position, locking means coacting with the handle for holding it in "on" position, whereby retrograde movement is prevented, owing to the lost motion connection when the switch is "on" and means for releasing or tripping the lock for the handle, the handle being movable automatically in a retrograde direction when released of its locking means for the tripping motion transmitting means.

50 The switch may be of any suitable form, size and construction and is here shown as

located in a suitable casing or box. I have here illustrated the switch as adapted to be used in a three wire system.

1 designates the box or case. The switch mechanism here illustrated comprises a plurality of switch members in the form of laminated arms 2 which move into and out of engagement with pairs of contacts 3, 4, and the contacts 3 being connected to terminals 5 which in turn are connected to the service wires entering one end of the box; and the contacts 4 being connected to fuse contacts 6, which are connected through fuses 7 to fuse contacts 8 paired with the contacts 6, these contacts 8 being connected to terminals 9 which are connected to the service wires leaving the other end of the box.

The contacts 3, 4 and the switch mechanism are mounted on a suitable base 10 which is secured in the box in any suitable manner, and the fuse contacts are also mounted on such base. The box is provided with a cover 12 hinged at 13 thereto and permanently held in position by screws 14 and 15 such cover 12 is also formed with a door 15 opposite the fuses of the fuse compartment, this door being normally held closed by a latch 16.

55 The means for actuating the switch member, as here illustrated, comprises a rock shaft 17 carried in a frame 18, a handle 19 and motion transmitting means between the handle 19 and the shaft 17 comprising a shaft 20 journaled in one side of the box 20 and coupled at its inner end by a nut at the coupling 21 to the shaft 17. The frame 18 is mounted on the base 10. The motion of the shaft is transmitted to the carrier from the switch arms by any suitable mechanism unnecessary to describe and unnecessary for understanding this switch operating mechanism. It is sufficient for an understanding of this switch operating mechanism to bear in mind that the rocking of the shaft upon the movement of the handle upwardly in this arrangement of the switch closes the switch and the movement of the handle in the opposite direction effects the opening of the switch.

100 As here illustrated, the handle 19 is mounted on the outer end of the shaft 20 to rotate about the same and is connected to the shaft 20 by a lost motion connection. This lost motion connection is here illus- 105

110

trated as in the nature of a pin and slot, and comprises an outwardly extending arm or shoulder 22, here shown as provided on a collar 23 fixed to the shaft 20 and a laterally extending pin or shoulder 24 on the hub 25 of the handle 19, the pin 24 extending into the path of the shoulder 22. Upon movement of the handle in one direction, as upwardly, the pin 24 engages the shoulder 22 and rocks the shafts 20 and 17 to bring the arms 2 in contact with the contacts 3, 4.

The locking means for holding the switch in its "on" position, as here shown, coacts directly with the collar 23, is movable automatically into operative position, and is released by the movement of the handle downwardly when the handle is moved relatively to the shaft 20 in a retrograde direction, such movement being permitted by the lost motion connection.

In the illustrated embodiment of my invention, the locking means is a latch 26 pivoted on a stud 27 extending from one side of the box, the latch having an engaging end 28 movable into engagement with an outwardly extending arm or shoulder 22 provided on the collar 23. The stud 27 is arranged on one side of the shaft 20 and the engaging end of the latch 26 on the diametrically opposite side, and a spring 29 for automatically moving the latch 26 into its operative position, is connected to the stud 27 on one side of such stud and extends obliquely across a straight line passing through the stud 27 and the point of contact of the engaging end of the latch 26 with the arm 22 and is connected at its other end to the latch 26 on the opposite side of such line. As here illustrated, the engaging end of the latch 26 is adjustable and it consists of a set screw 30 threading through the end of the latch 26 remote from the stud 27, the set screw 30 being arranged substantially radial with the stud 27. Usually, the arm 22 of the collar 23 is provided with a roller 31 with which the set screw 30 coacts. A suitable adjustable part, as a set screw 30^a carried by an arm 23^a on the collar 23 limits the movement of the latch 26.

This latch 26 is tripped during the retrograde movement of the handle lever 19 by the pin 24, which pin moves into engagement with the shoulder or face 32 provided on the latch 26 in the path of such pin 24.

The opening of the switch is preferably controlled by means coacting with the handle 19, this means being here shown as a latch 33 coacting with a shoulder 34 on the hub 25 of the handle 20, this latch being operable either by hand or by low voltage release means. The latch 33 is here illustrated as in the form of a bell crank lever mounted on the stud 27, one arm thereof coacting with the shoulder 34 on the hub of the handle 19 and the other arm 35 having connected there-

to a trip member 36. This member 36 can be used as a handle, or operated by release mechanism. Obviously, upon the tripping of the latch 33, the handle 19 will fall down by its own weight from the position shown in Figure 2, causing the pin 24 thereon to strike the shoulder or face 32 on the lock 26 and trip such lock 26 thus releasing the shaft 20, so that, the switch opens or is free to open by the resiliency of the arms 2 or by other springs. The member 36 is shown as a rod having a handle 37.

Usually the automatic or low voltage release means for controlling the opening of the switch, is employed. This means illustrated comprises a pair of coils 38, 39 suitably supported within a casing 40 mounted on the outside of the box 1, the coils being connected respectively to the outside main conductors of the circuit and to the central main conductor at the ends of the fuses 7 remote from the switch members 2, that is, at the fuse contacts 8 or the terminals 9, movable cores 40, 41 arranged within the coils, and means for transferring the movement of the cores 40, 41 to the latch 33, the coil 38 being connected at its upper end to wire terminal 9 of one outside main conductor as that on the right hand of Figure 1 by a wire 42 and the lower end of the coil 39 being connected by a wire 43 to the contact 8 in the other outside main conductor, and the inner end of the both coils being connected preferably by a common conductor 44 to the fuse contact 8 of the central main conductor.

This means for transferring the movement of the cores 40, 41 to the trip latch 33 comprises the rod 36 which is movable end-wisely through the casing 40 and through the cores 40, 41, the rod having shoulders 45, 46 arranged in the path of the cores 40, 41 respectively. A suitable spring 47 acts on the lever arm 35, this spring being shown as interposed between the lever arm 35 and the top of the casing 40.

In operation, when the switch is "on" the rod 36 is moved upwardly by the spring 47 and this spring moves the latch lever 33 into engagement with the shoulder 34 on the handle to hold the handle in "on" position. During the movement of the handle to its "on" position, it rocks the shaft 20 by reason of the pin 24 engaging the shoulder 22 on the collar 23 and, when the switch reaches its "on" position, the spring 29 pulls the latch 26 into engagement with the arm shoulder 22 of the collar 23. To open the switch, the rod 36 is pulled tripping the latch 33 and releasing the handle 19, so that it falls by gravity and trips the latch 26 for the shaft 20 or, if either of the fuses 7 in the outside mains burns out, or, if there is any other reason for the circuit being broken through such outside main, the correspond-

ing coil 38 or 39 will be deenergized permitting the armature or core 40 or 41 to drop and act as a hammer on the shoulder 45 or 46, thus moving the rod 36 downwardly and tripping the latch 33. Upon the tripping of the latch, the handle 20 will drop by gravity and trip the latch 26 and hence permit the switch to open.

If, for any reason, the circuit becomes broken through, the central main conductor, as, if the fuses 7 in the central main burns out, the resistance of the magnet coils 38, 39 is so great that the magnets are not powerful enough to hold the armatures or cores 40, 41 elevated and both cores drop and act on the shoulders 45, 46 as hammers to release the latch 33, so that, the switch opens, as before described.

What I claim is:

1. In a switch mechanism, the combination of a movable member and operating mechanism therefor comprising a handle and motion transmitting means between the handle and the switch member and locks coacting respectively with the motion transmitting member and with the handle, said locks being movable automatically into their operative positions and the handle having means for tripping the lock of the motion transmitting member.

2. In a switch mechanism, the combination of a movable switch member and operating mechanism therefor comprising a handle and a motion transmitting element between the handle and switch member, spring pressed locks coacting respectively with said element and the handle and movable automatically by the springs into their operative position, the handle having means for tripping the lock of the motion transmitting element and means for tripping the lock of the handle.

3. In a switch mechanism, the combination of a switch and operating means therefor comprising a handle, movable transmitting means between the handle and the movable switch member, a lock movable automatically into engagement with the motion transmitting means when the same is in its position assumed when the switch is "on", a lock coacting with the handle to hold it in its position assumed when the switch is "on", the handle having means for coacting with the first mentioned lock to trip the same and operating to release the motion transmitting means.

4. In a switch mechanism, the combination of a movable switch member and operating means therefor comprising a handle, motion transmitting means between the handle and the switch member, the handle being connected to the motion transmitting means by a lost motion connection, a spring pressed lock for holding the motion transmitting means in its operative position occupied

when the switch is "on", said lock being movable automatically by its spring into engagement with the motion transmitting means and the handle having means coacting with the lock to move it against its 70 spring out of operative engagement with the motion transmitting means.

5. In a switch mechanism, the combination of a movable switch member and operating means therefor comprising a handle 75 and motion transmitting means between the handle and the switch member, the handle being connected to the motion transmitting means by a lost motion connection, the handle being movable automatically to "off" position, a lock for holding the motion transmitting means in its operative position occupied when the switch is "on", said lock being movable automatically into engagement with the motion transmitting means, the 80 handle having means coacting with the lock to move it out of operative engagement with the motion transmitting means, and a second lock coacting with the handle and movable automatically into operative engagement 85 therewith when the handle is moved to its position occupied when the switch is "on".

6. In a switch mechanism, the combination of movable switch member, operating mechanism therefor comprising a shaft movable about an axis, a handle connected to the shaft by lost motion connection, locks coacting respectively with the handle and the shaft to hold them in their positions assumed when the switch is "on", said locks being 90 movable automatically into their operative positions, the handle having means for tripping the lock for the shaft when the handle is moved in a retrograde direction relatively to the shaft and means for tripping the lock 95 to the handle.

7. In a switch mechanism, the combination of movable switch member, operating mechanism therefor comprising a shaft 100 movable about an axis, a handle mounted on the shaft and movable about the same, a lost motion connection between the handle and the shaft, locks arranged to hold the handle and the shaft in their positions assumed when the switch is "on", said locks 110 being movable automatically into their operative position and the handle having means for tripping the lock for the shaft when the handle is moved in retrograde direction relatively to the shaft and means for 115 tripping the latch to the handle.

8. In a switch mechanism, the combination of a movable switch member, operating mechanism therefor comprising a shaft provided with a pair of outwardly extending arms, a handle mounted on the shaft and having a shoulder movable into engagement with one of said arms whereby the handle is connected to the shaft by a lost motion connection, a latch coacting with the other arm 120 125

- of the shaft and movable automatically into engagement therewith when the shaft is operated to the "on" position and a lock for holding the handle in its "on" position, said lock being movable automatically into its operative position, the handle being arranged to trip the lock for the shaft when the handle is moved in a retrograde direction and means for tripping the lock of the handle.
9. In a switch mechanism, the combination of a movable switch member, operating mechanism therefor comprising a shaft movable about an axis and having a collar thereon formed with outwardly extending shoulders, a handle mounted on the shaft adjacent the collar and having a shoulder movable into engagement with one of the former shoulders whereby the handle is connected to the switch by a lost motion connection, a latch arranged to engage the other shoulder of the collar when the switch is in its "on" position, the latch being arranged in the path of the shoulder on the handle to be tripped by the handle when the handle is moved in retrograde direction, and a latch

movable automatically into engagement with the handle to lock it in its "on" position and means for tripping the latch for the handle.

10. In a switch mechanism, the combination of a movable switch member and operating means therefor comprising a shaft movable about an axis having a pair of shoulders movable thereon, a handle having a shoulder for engaging one of the former shoulders to turn the shaft, a latch coacting with the handle to normally hold it in its position assumed when the switch is "on", a latch coacting with the other shoulder of the shaft for holding the shaft in its position assumed when the switch is on, means for releasing the first mentioned latch, the second mentioned latch being arranged to move out of its operative engagement by the handle after the handle has been released from the first mentioned latch.

In testimony whereof, I have hereunto signed my name, at Syracuse, in the county of Onondaga, and State of New York, this 3rd day of October, 1923.

CARL H. BISSELL.
